UNITED STATES PATENT OFFICE.

JOSEF MATHEIN, OF NEW HAVEN, CONNECTICUT, ASSIGNOR TO E. & H. T. ANTHONY & CO., OF NEW YORK, N. Y.

PHOTOGRAPHIC KIT.

SPECIFICATION forming part of Letters Patent No. 674,810, dated May 21, 1901.

Application filed May 10, 1900. Serial No. 16,146. (No model.)

To all whom it may concern:

Be it known that I, JOSEF MATHEIN, a citizen of the United States, and a resident of New Haven, in the county of New Haven and State 5 of Connecticut, (having my post-office address at 21 Elliot street, in said city of New Haven,) have invented a new and useful Photographic Kit, of which the following is a specification, reference being had to the accompanying 10 drawings, in which—

Figure 1 illustrates an elevation of the kit, showing a glass plate within it. Fig. 2 is a vertical sectional view taken on the medial line of Fig. 1. Fig. 3 is a view showing how 15 two of my kits, each inclosing a plate, may be supported by each other so that the plates may drain and dry. Fig. 4 is a detail showing the method of forming the ledges which support the glass plate out of the material 20 which constitutes the kit itself.

Photographers' kits as heretofore made have necessarily been very perishable. They have usually been made of material which is liable to split and become warped and which 25 will not withstand the application of moisture, much less any contact with the chemicals used in the developing process. They have necessarily been made very thin, because they must not be thicker than the glass plates 30 which they support, for if so the plates would not be in proper focal plane. Moreover, the attachment of the little ledges or clips which support the glass plates and confine them within these thin kits has necessitated deli- 35 cate workmanship in the original construction of them and also adds to their perishability, because of the necessarily insecure attachment of these devices to the body of the kit.

My invention consists in making the kit of 40 such material that it may be constructed all of one piece, there being no joints at the corners or at any other place, and the material must be such also that the ledges which confine the glass plate within the kit may all be 45 swaged or pressed out from the single piece constituting the kit. Thus there is necessity for but one separate part, and that is a little latch or button which swings over one edge of the glass plate to confine it within the kit, 50 and this part, owing to the character of the material from which the kit is made, may be

securely and in a durable manner attached to it.

My invention also embodies the use of a special material—to wit, the metal aluminium— 55 from which to make the kits. I prefer this material to all others, although I do not limit my invention to its use, since when it is employed the requisite thickness in the kit can be secured without forming any ribs, projecting points, or ledges upon it, which are apt to become distorted during use, and yet the weight of the kit is so slight that a full set of plates can be carried with a camera for amateur or other use at a minimum of weight. 60 65

The advantages I secure are as follows:

First. The kit is made of one piece only, with the exception of the little latch referred to, and that may be attached in a durable manner. Consequently it is what may be called 70 a "jointless" kit.

Second. The piece cut from the center of the kit may itself be used to make a kit of the next smaller size, thus economizing material and cheapening the manufacture. 75

Third. The kit can be immersed in the developer, if necessary, without injury to either it or the chemicals.

Fourth. A slot formed in the end or side of the kit may be used as a means of supporting two of them in a manner to be described, so that the plates will drain and dry effectively. 80

Referring to the drawings, A is the body of the kit, and B a glass plate within it. 85

C C C C are four ledges which are swaged or pressed out of the material forming the kit itself.

D is a single ledge, likewise swaged or pressed from the material forming the kit; but it projects from the opposite side of the kit from the ledges C C, &c. 90

E is an ordinary button or latch which is fastened by a pivot F at one end of the kit opposite the ledge D. 95

G is a slot cut through the body of the kit, within which the corner of another kit H (see Fig. 3) may be placed, whereby two kits will each support the other during the draining and drying of the developed plates. 100

The dies that form the ledges are made to work accurately, so that the surfaces of the

ledges against which the glass plate rests hold it in the same plane or substantially the same plane as that occupied by the body of the kit itself, and the metal of which the kit is made is of substantially the same thickness as the glass plate, so that the proper focal plane of the latter will be maintained.

The operation is as follows: To introduce a place within one of my kits, it is first introduced in such manner that one of its ends passes between the ledges C and D, whereby it is supported against movement in either direction at that end, and then being properly entered within the opening through the kit and dropped upon the ledges C at the opposite end the button E is turned over it, as shown in Figs. 1 and 2, whereby it is securely held in position.

As heretofore stated, I prefer to use the metal aluminium from which to make the kits; but rubber or celluloid may be employed. If so, the ledges will obviously be formed at such stage in the manufacture as will enable this to be done, and if metal other than aluminium be employed, then if of a character which would be affected by the chemicals of the solution or which would itself injure the solutions they should be protected by lacquer, plating, or otherwise.

30 3. I claim—

1. A jointless photographer's kit made of a single piece of material of substantially the thickness of the glass plate it is to support, and having ledges against which the plate may rest and be supported within the kit and in the same plane with it, said ledges being pressed from the material of which the kit is made, for the purposes set forth.

2. A jointless photographer's kit made of a single piece of material of substantially the thickness of the glass plate it is to support, ledges against which the plate may rest made integral with the kit itself, and a slot through one side of the kit adapted to receive the corner of another kit, for the purposes set forth. 45

3. A jointless photographer's kit made of a single piece of material of substantially the thickness of the glass plate it is to support, ledges against which the plate may rest pressed from the material of which the kit is made, one at least of said ledges being presented oppositely to the others, and a button adapted to swing over the edge of the plate, for the purposes set forth. 50

4. A jointless photographer's kit made of a single piece of aluminium of substantially the same thickness as that of the plate it is to support, ledges pressed from the material of which the kit is made adapted to support the plate, and a button adapted to be swung over one edge of the plate, for the purposes set forth. 55

5. A jointless photographer's kit made of a single piece of aluminium having ledges for the support of the plate pressed from it and presented in opposite directions, and a button to coact with one or more of the ledges for the confinement of the plate within the kit, for the purposes set forth. 65

Signed at New Haven, in the county of New Haven and State of Connecticut, this 12th day of April, A. D. 1900.

JOSEF MATHEIN.
